UNITED STATES PATENT OFFICE.

WILLIAM ELIAS MILLER, OF CRIPPLECREEK, COLORADO.

PEN-CLEANER.

SPECIFICATION forming part of Letters Patent No. 717,595, dated January 6, 1903.

Application filed September 8, 1902. Serial No. 122,628. (No model.)

To all whom it may concern:

Be it known that I, WILLIAM ELIAS MILLER, a citizen of the United States, residing at Cripplecreek, in the county of Teller and State of Colorado, have invented a new and useful 5 Pen-Cleaner, of which the following is a specification.

The invention relates to improvements in pen-cleaners.

10 The object of the present invention is to improve the construction of pen-cleaners and to provide a simple, inexpensive and efficient device capable of enabling a pen to be readily cleaned and dried and adapted also 15 to prevent the ink from being thrown out of it by the bristles of a brush.

The invention consists in the construction and novel combination and arrangement of parts hereinafter fully described, illustrated 20 in the accompanying drawings, and pointed out in the claims hereto appended.

In the drawings, Figure 1 is a perspective view of a pen-cleaner constructed in accordance with this invention. Fig. 2 is a longitudinal sectional view of the same. Fig. 3 is 25 a transverse sectional view. Fig. 4 is a plan view. Fig. 5 is a transverse sectional view showing another form of brush.

Like numerals of reference designate corresponding parts in all the figures of the drawings.

1 designates an oblong case, designed to be 30 constructed of glass or other suitable material and composed of sides 2 and 3, ends 4 and 5, and an inclined top 6. The casing is provided at its front with a longitudinal opening 7, formed by cutting away a portion of the front side and the top of the casing. The end 4 has its upper portion tapered to provide 35 opposite inclined edges, as clearly shown in Fig. 1, and the other end has its upper edge inclined downward and rearward from the top of the front side of the casing to the back of the same. The front edge of the top 6 extends 40 from the apex of the end 5 diagonally across the front portion of the casing to the apex of the end 4, making the opening 7 tapering in plan view, as shown in Fig. 4, and presenting a front pen-guide, which is adapted 45 to direct a pen across a brush 8. The pen-

guide extends forward from the apex of the end 4 and is disposed diagonally of the brush, and it terminates short of the end thereof. When a pen is introduced into the opening at the rear end of the pen-guide, it is carried 55 into contact with the brush, and by drawing it longitudinally of the guide the pen is carried diagonally over the brush to the end of the guide, where it is drawn outward by a movement transversely of the brush, thereby 60 cleaning the nibs of the pen and rotating the brush, as hereinafter explained. The particular construction of the casing also prevents ink from being thrown out of the opening 7 when a pen is wiped on the brush. 65

The bottom of the casing consists of a removable slide 9, arranged in grooves 10 of the front and back sides of the casing and adapted to be readily removed to afford access to the brush 8. 70

The brush 8 is cylindrical to provide a pen-wiper of large area, and it is adapted to be rotated by the pen when the same is drawn across it at the end of the pen-guide. This will bring a fresh portion of the brush to the 75 opening, and the entire surface of the brush will be exposed in this manner to cause the same to be uniformly used. The central shaft or body portion 11 of the brush is provided at one end with a tapered portion or journal 12 to fit a bearing-opening of the adjacent end 80 of the casing. The other end of the shaft or body portion of the brush is provided with a longitudinal socket 13, having interior screw-threads and adapted to receive a threaded 85 shank or screw 14, provided with a tapered or conical head 15 to fit in a bearing at the other end of the casing. The construction may be simplified by arranging an oblong brush 16 within the casing, as illustrated in 90 Fig. 5 of the drawings.

It will be seen that the pen-cleaner is exceedingly simple and inexpensive in construction, that it is adapted to prevent it from splashing from the casing, and that it presents a pen-guide disposed diagonally of the brush and adapted to permit a pen to be quickly and thoroughly cleaned and capable also of rotating the brush to present different portions of the brush for use. 95 100

What I claim is—

1. A device of the class described comprising a brush, and a casing for the brush provided with a pen-guide disposed diagonally 5 of the brush, substantially as described.
2. A device of the class described comprising a brush, and a casing for the brush provided with a pen-guide disposed diagonally 10 of the brush and arranged at the front of the casing at the top thereof, substantially as described.
3. A device of the class described comprising a brush, and a casing for the brush and having an opening forming a pen-guide disposed diagonally of the brush and terminat- 15

ing short of one end thereof, substantially as and for the purpose described.

4. A device of the class described comprising a rotary brush, a casing receiving the brush and having an opening forming a pen-guide disposed diagonally of the brush and terminating short of one end of the same, substantially as and for the purpose described. 20

In testimony that I claim the foregoing as my own I have hereto affixed my signature in 25 the presence of two witnesses.

WILLIAM ELIAS MILLER.
